(57) **CLAIM**

The ornamental design for a collapsible box stove, as shown and described herein.

DESCRIPTION

FIG. 1 is an elevated, perspective view of the collapsible box stove in a first configuration in accordance with our invention;

FIG. 2 is a front view of FIG. 1;

FIG. 3 is back view of FIG. 1;

FIG. 4 is a side view of FIG. 1;

FIG. 5 is an opposite view of FIG. 4;

FIG. 6 is a top view of FIG. 1;

FIG. 7 is a bottom view of FIG. 1;

FIG. 8 is an elevated, perspective view of the collapsible box stove in a second configuration in accordance with our invention;

FIG. 9 is a front view of FIG. 8;

FIG. 10 is back view of FIG. 8;

FIG. 11 is a side view of FIG. 8;

FIG. 12 is an opposite view of FIG. 11;

FIG. 13 is a top view of FIG. 8; and,

FIG. 14 is a bottom view of FIG. 8.

The broken lines depict portions of the collapsible box stove that form no part of the claim. The broken lines act as boundaries of the claim where they intersect claimed surfaces.

1 Claim, 10 Drawing Sheets
